CLAIM

The ornamental design for a flame-shaped printed circuit board for an electronic candle or other electronic light, as shown and described.

DESCRIPTION

FIG. 1 is a perspective view of a flame-shaped printed circuit board for an electronic candle or other electronic light showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines of FIGS. 1-8 are provided for purposes of illustration and form no part of the claimed design of the present application.

1 Claim, 5 Drawing Sheets
